UNITED STATES PATENT OFFICE

REUBEN HALEY, OF BEAVER, PENNSYLVANIA, ASSIGNOR TO STREET LUMINAIRE COMPANY, OF CHICAGO, ILLINOIS, A CORPORATION OF ILLINOIS

DESIGN FOR GLASS

Application filed January 21, 1929. Serial No. 29,689. Term of patent 3½ years.

To all whom it may concern:

Be it known that I, REUBEN HALEY, a citizen of the United States, and a resident of Beaver, in the county of Beaver and State of Pennsylvania, have invented a new, original, and ornamental Design for Glass, of which the following is a specification, reference being had to the accompanying drawing, forming part of the present application, in which—

Figure 1 is a face view of a piece of glass, showing my new design; and

Figure 2 is a sectional view substantially on the line 2—2 of Fig. 1.

The dominant feature of the design con-

sists of the depressed triangular figures, each comprising three irregular sides or facets, said figures being continuous over the surface bearing the design, juxtaposed depressions having common crests which are rounded and which collectively define the superficial contour of the article bearing the design.

I claim:

The ornamental design for glass, substantially as shown and described.

In witness that I claim the foregoing as my invention, I have hereunto affixed my signature this 12th day of January, 1929.

REUBEN HALEY.
